UNITED STATES PATENT OFFICE.

REINHARD KLINGELHÖFFER, OF WERDEN-RUHR, GERMANY, ASSIGNOR TO FRIED.
KRUPP AKTIENGESELLSCHAFT, OF ESSEN-ON-THE-RUHR, GERMANY.

RECOOLING DEVICE FOR CONDENSING LOCOMOTIVES.

Application filed June 1, 1923, Serial No. 642,827, and in Germany June 28, 1922.

This invention relates to re-cooling devices for condensing locomotives of the kind which are arranged on a trail car, and it resides, more particularly, in that the re-cooling device comprises at both sides of the 5 trail car rows of walls inclined at an acute angle with relation to the direction of running and leaving between them a free space which is in communication with a blower.

10 In the drawings:

Fig. 1 is a side elevation of one embodiment of the subject matter of the invention, partly in a vertical longitudinal section;

15 Fig. 2 is a plan view corresponding to Fig. 1;

Fig. 3 is a section on the line 3—3 of Fig. 1;

Fig. 4 is a section on the line 4—4 of Fig. 1, seen from the left;

20 Fig. 5 is an elevation, similar to Fig. 1, of another embodiment of the subject matter of the invention, and

Fig. 6 is a plan view corresponding to Fig. 5.

25 Referring now to the drawings, the arrangement illustrated in Figs. 1 to 4 will be described first.

The underframe A¹ of the trail car A carries a water tank A². Mounted on the perforated sheet metal top a³ of the water tank A² vertically with relation to the plane of this sheet metal are two rows of parallel walls B which are inclined at an angle of about 30 to 60 degrees with relation to the 30 direction of running. The walls B do not extend as far as the vertical longitudinal middle plane of the trail car, so that the two rows of walls leave between each other a free space C extending in the direction of

40 the last-mentioned plane. The walls B consist either of smooth sheet metal, corrugated sheet metal, wire sieves or narrow meshed expanded metal. The space C is closed at its front end by a transverse wall a⁴ of the trail car, it gradually enlarges rearwardly and is at its rear end in communication with the suction pipe of a mechanically driven blower D. The casing of the blower is provided with a pipe d¹ which projects into an enlarged portion a⁵ of the water tank A².

45 The water to be cooled is fed to the re-cooler by a pipe E which forks into two pipes e¹ and e² above the transverse wall a⁴. The pipes e¹ and e² are provided in the ordinary manner with fine openings from which the

water to be cooled flows between and over the walls B. The connection of the tank A² with the condenser which is arranged on the locomotive, is established by a pipe line not shown in the drawings.

50 When the locomotive is running, the air streaming along the trail car A will pass through between the walls B into the space C and will be drawn off from the latter by the blower D. A strong air draught is thus 55 produced between the walls B, which draught will quickly cool the water trickling down the walls B. In the blower D the water-drops carried along by the cooling air will be thrown against the wall of the blower 60 casing by the action of the centrifugal force and caused to flow through the pipe d¹ into the tank A². As the space C enlarges gradually towards the blower D a sufficiently 65 large cross-section is produced for the outlet of the air entering between the cooling 70 walls B.

75 With the embodiment represented in Figs. 5 and 6, the cooling walls are replaced by flat zig-zag tubes F which are parallel with 80 relation to one another and through which flows the cooling water of the condenser or, in special cases, the steam to be condensed. When the locomotive is under extraordinary 85 loads, the cooling action of the air streaming past the tubes F may, in this instance, be increased by cooling water which is caused to trickle down over the zig-zag tubes and supplied by an additional cooling water tank. The zig-zag tubes may also be connected "in series" that means arranged behind one another.

Claims:

1. In combination with a vehicle, a liquid 95 cooler mounted thereon, said cooler comprising a multiplicity of cooling elements arranged at an angle to the longitudinal axis of the vehicle whereby air is deflected between said elements on a travelling movement of the vehicle, and means for delivering a liquid to be cooled to said elements whereby the liquid passes along said elements in heat exchanging relation with the incoming air.

100 2. In combination with a vehicle, a liquid 105 cooler mounted thereon, said cooler comprising a multiplicity of cooling elements arranged at an angle to the longitudinal axis of the vehicle whereby air is deflected between said elements on a travelling move- 110

ment of the vehicle, auxiliary means for forcing the air to the rear of the vehicle after its passage between said elements, and means for delivering a liquid to be cooled 5 to said elements whereby the liquid passes along said elements in heat exchanging relation with the incoming air.

3. In combination with a vehicle, a liquid cooler mounted thereon, said cooler comprising 10 a multiplicity of cooling elements arranged at an angle to the longitudinal axis of the vehicle whereby the air is deflected between said elements on a travelling movement of the vehicle, a centrifugal blower 15 having its intake at the rear of the rear-most of said elements, and means for delivering a liquid to be cooled to said elements whereby the liquid passes along said elements in heat exchanging relation with the 20 incoming air.

4. Reflux cooler for condensing locomotives consisting of two spaced series of cooling elements, the respective elements of said series being angularly disposed relative to 25 the longitudinal axis of the locomotive whereby, on a travelling movement of the locomotive, air is deflected by said elements into the space existing between said series, and means for delivering a liquid to be 30 cooled to said elements whereby the liquid passes along said elements in heat exchanging relation with the incoming air.

5. Reflux cooler for condensing locomotives consisting of two spaced series of cooling 35 elements, the respective elements of said series being angularly disposed relative to the longitudinal axis of the locomotive whereby, on a travelling movement of the locomotive, air is deflected by said elements 40 into the space existing between said series, auxiliary means for forcing the incoming air rearwardly in said space, and means for delivering a liquid to be cooled to said elements whereby the liquid passes along said 45 elements in heat exchanging relation with the incoming air.

6. In combination with a trailer, a reflux cooler for condensing locomotives mounted thereon, said cooler comprising a series of 50 substantially vertical cooling elements at each side of the trailer, the space between

said series enlarging towards the rear of the trailer, the respective elements of said series being angularly disposed relative to the longitudinal axis of the trailer whereby, 55 on a travelling movement of the trailer, air is deflected by said elements into the space existing between said series, and means for delivering a liquid to be cooled to said elements whereby the liquid passes along said 60 elements in heat exchanging relation with the incoming air.

7. In combination with a trailer, a reflux cooler for condensing locomotives mounted thereon, said cooler comprising a series of 65 substantially vertical cooling elements at each side of the trailer, the respective elements of said series being angularly disposed relative to the longitudinal axis of the trailer whereby, on a travelling movement of the trailer, air is deflected by said 70 elements into the space existing between said series, a centrifugal blower having its intake at the rear of said space, and means for delivering a liquid to be cooled to said 75 elements whereby the liquid passes along said elements in heat exchanging relation with the incoming air.

8. In combination with a trailer, a reflux cooler for condensing locomotives mounted 80 thereon, said cooler comprising a series of substantially vertical panels at each side of the trailer, the respective panels of said series being angularly disposed relative to the longitudinal axis of the trailer whereby, 85 on a travelling movement of the trailer, air is deflected by said panels into the space existing between said series, a centrifugal blower having its intake at the rear of said 90 space, a casing for said blower, a reservoir in communication with said casing, and means for delivering a liquid to be cooled to said panels whereby the liquid passes along said panels in heat exchanging relation with the incoming air, said blower 95 casing serving to collect particles of water thrown against it by the blower and guide them into said reservoir.

The foregoing specification signed at Cologne, Germany, this 14th day of May. 100 1923.

REINHARD KLINGELHOFFER.
